(57) **CLAIM**

The ornamental design for a lighting fixture, as shown and described.

DESCRIPTION

FIG. 1 is a bottom perspective view of a lighting fixture depicting a new design;

FIG. 2 is a top perspective view thereof;

FIG. 3 is a front elevation view thereof;

FIG. 4 is a back elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken line disclosures in the views represent portions of the lighting fixture that form no part of the claimed designs. The break line in the chain reflects that its length may vary.
